Frank Stevens, Inventor,
Mr. J. Martin, Jr., Attorney.

UNITED STATES PATENT OFFICE.

FRANK STEVENS, OF PHILADELPHIA, PENNSYLVANIA.

SOUND-TRANSMITTING APPARATUS.

1,273,107.

Specification of Letters Patent. Patented July 16, 1918.

Application filed January 17, 1917. Serial No. 142,921.

To all whom it may concern:

Be it known that I, FRANK STEVENS, a citizen of the United States, residing at Philadelphia, in the county of Philadelphia and State of Pennsylvania, have invented a new and useful Sound-Transmitting Apparatus, of which the following is a specification.

My invention relates to improvements in means for transmitting all sounds, vocal, instrumental, etc., of whatsoever nature, reproduced by artificial means such as phonographs, talking machines and the like, and its use in conjunction with such devices affords ready facility for reproducing the sounds therefrom at widely separated points and at a distance, with great clearness and fidelity and in satisfactory volume.

My principal object is to provide efficient means for receiving and confining the sounds referred to and instantly transmitting them to divers distributing stations, as for instance, where it is desired to use a talking machine as an adjunct to a moving picture apparatus, my device is useful in taking and transmitting to an auditorium, long continued records requiring more than one disk or cylinder, as will more fully appear, together with other novel and useful objects, as the description proceeds.

I attain these objects by the mechanism illustrated in the accompanying drawings, in which—

Figure 1, is a plan view of the device; Fig. 2, a similar view with the top, B¹, removed; Fig. 3, a rear elevation with the back wall, B³, and some underlying parts partially broken away to show interior construction; Fig. 4, a plan view of a modified form; and, Fig. 5, a side elevation of the same, having a side removed and parts broken away to show interior construction. It is to be noted that the wiring shown is merely diagrammatic, to indicate the mode of conducting the circuits to the exterior of the apparatus.

Similar indices refer to similar parts throughout the several views.

Believing a very apt illustration of the scope of my invention to be one in which it is shown coupled with a talking machine having two turn tables—(or mandrels)—which alternately engage separate records so as to permit of the use of an indefinite number, and thus to afford a continuous per-

formance, I have shown such an arrangement in Figs. 1, 2 and 3, although it is to be understood that I do not intend to thus restrict my invention to such limited use. As shown in Figs. 4 and 5, the sound conducting arms C, C¹, may be rotated so as to engage separate talking machines and, it is self-evident from the several views without additional specific illustration, that the number and arrangement of these arms may be increased and varied to engage several single machines, or one or more machines employing several reproducers each. Therefore, for the purpose of illustrating my invention, I have shown in the accompanying drawings the form thereof which is, at present preferred by me, although it is to be understood that the various instrumentalities of which my invention consists can be variously arranged and organized and that my invention is not to be limited to the precise arrangement and organization as shown and described and that I reserve the right to re-organize and rearrange these instrumentalities within the scope of my invention.

Referring to Figs. 1, 2 and 3,—to a continuously operating talking machine, A, provided with two reproducers (not shown) is attached my device, B, as indicated at 2, having interposed between all adjacent parts of the two machines a shield of rubber or other suitable material, 1, to deaden the effect of all mechanical sounds and vibrations which might otherwise interfere with and mar the clearness of the desired sounds entering through the arms, C, C¹, which communicate with the reproducers of the talking machine.

The instrument B is a substantially airtight and sound-proof receptacle having no openings except those provided for the entrance of the reproduced sounds (as shown in broken lines at 3 in Figs. 3 and 5) and is preferably composed of vulcanized fiber which material greatly adds to the sound proof quality as well as affording insulation from chance electrical disturbances and presenting a very elegant means for locating as desired the conductors from within to the exterior. To each opening 3, an arm, C, C¹, is articulated in such manner as to make a substantially sound-proof and air-tight joint, yet susceptible of such smooth and easy motion as may be required to permit of the proper action of the arm. These

sound entrances 3, lead to an interior chamber B^5 , formed by the continuous ring-shaped wall 12, the top, B^1 , and bottom, B^2 , of the case. This annular wall is made of sound reflecting material and is firmly held between the top and bottom. Interposed between this wall's upper edge and the top, B^1 , is a gasket 13, of material such as rubber or leather, adapted to form a tightly sealed joint, and a similar sealing member 14 is likewise disposed between the wall's lower edge and the bottom B^2 . These gaskets, 13 and 14, are shown as an integral part of the secondary or sealing wall, 15, which is composed of the same material as the gaskets and which surrounds the innermost wall, 12, and it is so disposed parallel therewith as to form a narrow air-space B^4 , all around between the two.

Within the sealed chamber, B^5 , thus provided, are suitably located one or more magnetic electric sound transmitters, such as are used on telephones, adapted to be influenced by the sounds entering, as already described through the arms, C , C^1 , and provided with the usual conductors 5, which are electrically connected with the bus bars, 16, suitably secured to the outside of one of the walls (the rear wall, B^3 , in this case, Fig. 3) of the case B , by metallic bolts 19, which penetrate the fiber wall and are held by nuts 20, which present contacts for the securing of the conductors. Such external leads or conductors as may be required for any particular result are, of course, attached to these bus bars whereby the sounds from the transmitters may be led to divers places without regard to distance, location or number and there reproduced in the usual way.

In order to accurately adjust the transmitter to the exact location, with relation to the arms, C , C^1 , necessary to produce the clearest results, each transmitter is slidably mounted on a rotatable carrier 6. Each carrier is pivotally secured to the case B by means of a threaded stem 7 whereby the carrier 6 may be rotated and set at any angle and at any desired distance from the wall and there securely clamped by nuts 17 and 18, one within and the other without the wall, and reinforced by the locking nut 8. Slots 9 are formed on each carrier 6 to engage suitable guides 10 on each transmitter, each guide being provided with a set screw 11. By this construction each transmitter may be moved longitudinally along its carrier and be set at any desired location with relation to the openings 3.

In Figs. 4 and 5, a slightly different arrangement of the openings 3 is shown, with a single large transmitter in lieu of several smaller ones. It is evident, without further illustration, that additional arms like C and C^1 may be fitted to the case B , that the number of transmitters may be accord-

ingly varied and that my apparatus may be employed with equal facility in conjunction with one talking machine, or with several.

Having thus explained the nature of my invention and described and shown a way of constructing the same, although without attempting to set forth all the forms in which it may be made, or all the modes of its use, what I do claim is—

1. In a device of the character described, in combination with a talking machine, a sound chamber attached thereto, intermediate means to exclude the transmission of mechanical sounds and vibrations to said chamber, sound conducting means between said chamber and the reproducer on said talking machine, transmitters for recording and reproducing sound waves within said chamber, and conductors from the transmitters to the exterior of said chamber.

2. In a device of the character described, in combination with a talking machine, a sound chamber attached thereto, intermediate means to prevent the transmission of mechanical sounds and vibrations to said chamber, sound conducting means between said chamber and the reproducer on said talking machine, transmitters for recording and reproducing sound waves within said chamber, means to alter and adjust the locations of said transmitters, and conductors from said transmitters to the exterior of said chamber.

3. A device of the character described, comprising a sound-proof and air-tight chamber, a fiber casing therefor, means for introducing therein sounds produced by a talking machine, a transmitter for recording and reproducing sound waves therein, means for adjusting the location of said transmitter, and conductors from said transmitter to the exterior of said casing.

4. A device of the character described, comprising a sound-proof and air-tight chamber having curvilinear walls, means for introducing into said chamber sounds produced by a talking machine, a transmitter for recording and reproducing sound waves within said chamber, means for adjusting the location of said transmitter, and conductors from said transmitter to the exterior of said chamber.

5. A device of the character described, comprising a sound-proof and air-tight chamber having curvilinear walls, a fiber casing therefor, means for introducing therein sounds produced by a talking machine, a transmitter for recording and reproducing sound waves therein, means for adjusting the location of said transmitter, and conductors from said transmitter to the exterior of said casing.

6. A device of the character described, comprising a sound-proof and air-tight chamber, means for introducing into said

- chamber sounds produced by a talking machine, a transmitter for recording and reproducing sound waves within said chamber, means for adjusting the location of said transmitter, conductors from said transmitter to the exterior of said chamber, and means to exclude mechanical sounds and vibrations from said chamber.
7. A device of the character described comprising a sound-proof and air-tight chamber having curvilinear walls, means for introducing into said chamber sounds produced by a talking machine, a transmitter for recording and reproducing sound waves within said chamber, means for adjusting the location thereof, conductors therefrom to the exterior of said chamber, and means to exclude mechanical sounds and vibrations from said chamber.
- 10 8. A device of the character described comprising a sound-proof and air-tight chamber having curvilinear walls, a fiber casing therefor, means for introducing therein sounds produced by a talking machine, a transmitter for recording and reproducing sound waves therein, means for adjusting the location of said transmitter, conductors therefrom to the exterior of said casing, and means to exclude mechanical sounds and vibrations from the interior of said casing.
- 15 9. A device of the character described, comprising a sound-proof and air-tight chamber having double walls composed of an inner wall of sound reflecting material and a secondary wall of sound deadening material, an air space between said walls, means for introducing into said chamber sound produced by a talking machine, a transmitter for recording and reproducing sound waves within said chamber, means for adjusting the location of said transmitter, conductors from said transmitter to the exterior of said chamber, and means to exclude mechanical sounds and vibrations from said chamber.
- 20 10. A device of the character described comprising a sound-proof and air-tight chamber having double walls composed of an inner wall of sound reflecting material and a secondary wall of sound deadening material, an air space between said walls, means for introducing into said chamber sounds produced by a talking machine, a transmitter for recording and reproducing sound waves within said chamber, means for adjusting the location thereof, conductors therefrom to the exterior of said chamber, and means to exclude mechanical sounds and vibrations from said chamber.
- 25 11. A device of the character described comprising a sound-proof and air-tight chamber having double curvilinear walls composed of an inner wall, a secondary wall surrounding the same, an air space between said walls, a fiber casing for said chamber, means for introducing into said chamber sounds produced by a talking machine, a transmitter for recording and reproducing sound waves within said chamber, bus bars on the exterior of said housing, and electrical conductors from said transmitter to said bus bars.
- 30 12. A device of the character described, comprising a sound-proof and air-tight chamber having double curvilinear walls composed of an inner wall, a secondary wall surrounding the same, an air space between said walls, a fiber casing for said chamber, means for introducing into said chamber sounds produced by a talking machine, a transmitter for recording and reproducing sound waves within said chamber, bus bars on the exterior of said casing, and electrical conductors from said transmitters to said bus bars.
- 35 13. A device of the character described comprising a sound-proof and air-tight chamber composed of an outside casing, an intermediate curvilinear wall, an innermost curvilinear wall, an air space between said casing and said intermediate wall and an air space between said intermediate and said innermost walls, orifices in said casing adapted to permit of the air-tight and movably fitting of tone arms from a talking machine, transmitters for recording and reproducing sound waves adjustably disposed within said chamber, bus bars on the exterior of said casing, electrical connections between said transmitters and said bus bars, and a rubber shield on the surface of said casing.
